UNITED STATES PATENT OFFICE.

JOHN H. UHL, OF BUFFALO, NEW YORK, ASSIGNOR OF ONE-HALF TO
GEORGE KEIPPER, SR., OF BUFFALO, NEW YORK.

NON-REFILLABLE BOTTLE.

No. 807,389.

Specification of Letters Patent.

Patented Dec. 12, 1905.

Application filed September 2, 1905. Serial No. 276,888.

To all whom it may concern:

Be it known that I, JOHN H. UHL, a citizen of the United States, residing at Buffalo, in the county of Erie and State of New York, have invented new and useful Improvements 5 in Non-Refillable Bottles, of which the following is a specification.

My invention relates to closures for receptacles, such as bottles, jars, and the like; and 10 its primary object is to provide a device of this character which will prevent a receptacle from being refilled, thereby obviating any liability of the sale of a substitute article for that contained originally in the receptacle, 15 whereby the sale of fine wines, liquors, medicines, and perfumes may be protected.

Another object of the invention is to provide a closure which is comparatively simple 20 of construction, cheap to manufacture, durable, and efficient.

The invention consists of the construction, combination, and arrangement of parts hereinafter fully described, claimed, and illustrated in the accompanying drawings, where- 25 in—

Figure 1 is a central sectional view of the upper portion of a receptacle, illustrating the application of my improved closure. Fig. 2 is a sectional view on the line 2 2, Fig. 1. Fig. 3 is a detailed central sectional view of the combined locking member and valve-casing. Fig. 4 is a similar view of the valve, and Fig. 5 is a similar view of the guard or plug.

Referring to the drawings by reference-numbers, 1 designates the neck of a receptacle, the same being provided at a point intermediate its ends with recesses 2. A guard or plug 3, which is preferably constructed of glass, is positioned within the neck 1. This 35 guard is of a cylindrical formation and has a diameter slightly less than the inner diameter of the neck 1, in order that the guard may fit snugly within the neck, said guard being provided with perimetral tortuous passages 4, through which the contents of the receptacle is poured. The guard at a point adjacent its upper end is provided with two diametrically-opposed recesses 5, which are adapted to register with the recesses 2 in the neck 1. 40 Extending from the recesses 5 to the bottom of the guards are grooves 6, which incline

downwardly and outwardly, as fully illustrated in Fig. 5 of the drawings.

I provide an aluminium member which performs the dual function of securing the 55 guard in applied position within the neck and of supporting and carrying the valve which prevents the receptacle from being refilled. This member is fully illustrated in Fig. 3 of the drawings and consists of a valve-casing 7, which is of a diameter equal to the diameter of the guard 3 and which is provided with a valve-opening 8. The upper edge of the casing 7 is situated closely to the bottom of the guard 3, and rising vertically therefrom and positioned within the grooves 6 are arms 9, these arms having their upper ends bent to provide heads 10, portions of which are situated in the recesses 2 and 5. A valve 11 is positioned within the casing 7 prior to 60 the application of the member to the guard 3. The valve is provided with a pendent portion 12, adapted to fit in and project through the opening 8, and on its upper edge with lugs 13, which engage the bottom of the guard 65 3 to limit the movement of the valve from its seat.

Before the closure is inserted within the neck 1 the guard, valve, and member are assembled, and owing to the inclination of the 70 groove 6 the closure may be easily inserted into the neck 1. When the heads 10 are brought into alinement with the recesses 2 in the neck 1, said heads through virtue of the 75 spring quality of the arms 9 are forced into said grooves 2, thereby limiting the downward movement of the closure and locking the same in applied position.

It is apparent that an instrument cannot be inserted so as to prevent the seating of the 80 valve 11 and that said member performs a dual function of securing the closure within the neck 1 and supporting and carrying the valve, thus obviating the necessity of forming a valve-seat within the neck.

From the foregoing description, taken in connection with the accompanying drawings, the construction and mode of operation of the invention will be understood without a further extended description.

Changes in the form, proportions, and minor details of construction may be made with-

in the scope of the invention without departing from the spirit or sacrificing any of the advantages thereof.

Having fully described and illustrated my invention, what I claim is—

1. In a device of the character stated, the combination with the neck of a receptacle, of a guard, a valve, and means for supporting the valve and locking the guard in applied position.

2. In a device of the character stated, the combination with the neck of a receptacle, of a guard arranged within the neck, a valve-casing, means carried by the valve-casing to secure the guard in applied position, and a valve mounted within the casing.

3. In a device of the character stated, the combination with the neck of a receptacle, of

a guard mounted within said neck, a valve-casing provided with an arm and a locking-head to secure the guard in applied position, and a valve mounted within the casing.

4. In a device of the character stated, the combination with the neck of a receptacle provided with a recess, of a guard provided with a recess and an inclined groove, a valve-casing provided with an arm occupying said groove and having a locking-head mounted within said recess, and a valve mounted within the casing.

In testimony whereof I affix my signature in presence of two witnesses.

JOHN H. UHL.
